UNITED STATES PATENT OFFICE.

ENGELBERT MUELLER, OF RESERVE TOWNSHIP, ALLEGHENY COUNTY,
PENNSYLVANIA.

ARTIFICIAL FOOT AND ANKLE-JOINT.

963,796.

Specification of Letters Patent. Patented July 12, 1910.

Application filed September 7, 1909. Serial No. 516,469.

To all whom it may concern:

- Be it known that I, ENGELBERT MUELLER, residing at Reserve township, in the county of Allegheny and State of Pennsylvania, a citizen of the United States, have invented or discovered certain new and useful Improvements in Artificial Feet and Ankle-Joints, of which improvement the following is a specification.
- 10 My invention relates to improvements in the construction of artificial limbs and the objects of my invention are simplicity of structure, facility of separation of parts, and durability.
- 15 In the accompanying drawings which form part of this specification Figure 1 shows in perspective view an artificial foot and lower leg in the construction of which my present invention is employed. The 20 parts are for purpose of illustration shown detached the one from the other. Fig. 2 is a side elevation of the foot and lower leg assembled. Fig. 3 is an end view in perspective of a foot alone. Fig. 4 shows in 25 elevation, and in two views, the hinge knuckles detached from one another.
- Parts which are repeated in the several figures bear the same reference numerals in each case.
- 30 I shall first describe the hinge-joint which forms part of my invention; I shall describe it in its application to an ankle joint of an artificial leg, but it will be understood that it is applicable not to the formation of that 35 particular joint only, but to other joints as well in artificial limb construction.
- The joint itself is made up of three members, two hinge-knuckles which are bolted to the two artificial limb parts which are to 40 be articulated and a hinge-pin which unites them. These two knuckle parts are shown at 1 and 2 in the drawings, and the hinge-pin is shown at 3. Each of these hinge-knuckles 1 and 2 is bolted to a limb part 45 and each knuckle protrudes to engage its fellow knuckle and to be secured to it by the knuckle-pin, to form the joint.
- In the articulated foot and ankle taken for purpose of illustration, it will be seen 50 that the hinge-knuckle 1 is carried on and forms the head of a bolt 4 whose shank protrudes into a recess 5 in the leg portion of this artificial foot, that the protruding shank is threaded and receives a nut 6 to secure the 55 whole. The hinge-knuckle 2 is bolted to the
- foot member by a bolt 7 of which it forms the head and this bolt is secured by the nut 8 which is conveniently arranged to seat in a countersunk recess in the sole of the foot. 60 The knuckles which form this hinge are 60 block and clevis form, and while the exact arrangement is immaterial it will be observed that the knuckle carried by the leg member is the clevis, the knuckle carried by the foot is the block, and the two are pinned 65 together by the hinge-pin 3. This hinge-pin 3 will in good construction be made large, to afford an extended bearing surface, and it is preferably hollow as shown, and is made hollow for the sake of lightness. Being 70 hollow, I find it convenient to utilize the hollow space within it as an oil cup. To this end an oil duct 9 is drilled through the wall of this hollow pin, to admit a flow of oil to the bearing surface of the joint. Some 75 absorbent substance saturated with oil inserted within the hollow pin will thus keep the joint lubricated. For the sake of strength, the knuckles and pin are preferably made of steel, and it will be found 80 advantageous, contributing to the durability of the structure, to place within the hole in the hinge-block 2, a bushing 10 of a soft metal, such as brass.
- A further feature of this hinge-joint construction is the building out of the hinge-block 2 to form a shoulder 11, which, as the parts swing, will abut against the face of the web 12 of the clevis, and such abutting will limit the pivotal movement. 85 This is done, as the drawings show, so that the rearward swing of the foot from its horizontal position is permitted, but the forward swing beyond a certain point is absolutely stopped. 90
- The hinge-joint as thus far described is so applied and assembled with the limb members which it articulates, that the limb members while securely held together in service may readily be detached from one another and the hinge-parts themselves be readily 95 detached from the limb members for purposes of replacement and repair. To the end that the hinge parts may readily be detached, each forms the head of a single bolt 100 shank which extends through one of the articulated limb members and, being secured by a single nut, the whole may readily be taken apart, and the hinge members separated from the limb members. To the end 105 110

that the articulated limb members may be separated without taking the structure apart, the hinge-pin is removable. But, to guard against its accidental removal and to 5 secure it when the parts are assembled, a particular construction is employed. One knuckle of the hinge, preferably the clevis member 1, is so mounted and carried in its limb member that by tightening the bolt of 10 which the knuckle froms the head, the hinge-pin, when in place within the knuckle is clamped against the body of the limb member, secure against accidental displacement. A loosening of the bolt, on the other 15 hand, leaves the pin free to be withdrawn and reapplied for purposes of separating and assembling.

In order that the structure may be compact, and that the hinge-pin may be the 20 more securely held against the body of the limb member, a groove, 16, is preferably formed in the limb member to receive and frictionally hold the pin. It will be understood that when the parts are assembled for 25 service the pin will preferably have no rotary movement upon the surface of groove 16, but will be stationary therein, and the knuckle 2 will swing upon it. And from this it will be understood that the lubrication 30 afforded by the oil duct 9 in the pin is over that portion of the outer surface of the pin upon which the knuckle 2 has bearing. As the joint turns, the pin will turn against the surface of the adjacent limb member, 35 and for the sake of compactness the pin rests in a groove formed in the surface of that member also. For durability, the wearing surface of this latter groove may be faced with raw-hide or other suitable material.

40 The pivotal movement of the limb members as thus far described is limited only by the positive stop within the joint itself; but the permissible movement is not left free and uncontrollable. Movement in one direction is limited by the positive stop already described; movement in the other direction is cushioned, preferably by a spring such as 45 13 (which ordinarily will be a coiled spring cased in buckskin) engaging opposite portions of the two limb members, and this spring is compressed as the jointed parts swing. In the foot construction illustrated, this spring 13 lies on the posterior side of the ankle joint, approximately at the tendon 50 of Achilles. But motion in the opposite direction too is preferably controlled and cushioned, to the end that as the joint turns and approaches a dead stop the movement will be checked and the stop will be less 55 abrupt. I have shown alternative means for affording such cushioning. In Fig. 1 opposite surfaces of the jointed limb members are arranged to engage one another upon a cushion 14 carried by one of said 60 surfaces, slightly in advance of the engage-

ment of the metal surfaces of the hinge-knuckles which brings the pivot movement to a dead stop. In Fig. 2 a coiled spring 14^a similar to spring 13 already described, placed anterior to the ankle joint between 70 the opposite limb members cushions the meeting of the abutting surfaces of the hinge-knuckles.

In the ankle joint illustrated some stress comes upon the "nose" of the leg member, 75 that is the portion immediately anterior to the ankle joint; and, since these artificial limbs are ordinarily formed of such light soft wood as willow, I obtain a strengthening at this point (Fig. 1) by the insertion 80 of a block of hard wood, 15 in the solid body of the leg member; to like effect, in the specific construction illustrated in Fig. 2, the spring 14^a is backed by a block of hard wood, 15.

85 My invention in its further details has to do with the construction of an artificial foot. An artificial foot is commonly made of an upper body of soft wood and a sole body of felt, and extending longitudinally on the 90 sole and over the ball of the foot is a strip of elastic, held tense to afford a desired elasticity to that part of the structure.

My invention, so far as concerns the foot construction, consists in inserting between 95 the upper and the sole bodies such as I have described, a strip or tongue of relatively tough and tenacious material, such as hard wood, to add materially to the life and strength of the whole structure, this strip 100 or tongue of tenacious material is preferably dovetailed into the bodies of material which forms the upper and sole parts of the foot. In employing the ankle joint such as I have described I cause the bolt 7 of the knuckle 105 which the foot member carries to be extended through this tongue of hard wood or like substance, and thus the tongue of hard wood contributes to the serviceability of the joint.

110 In the drawings, 18 represents the upper part of the foot, which will preferably be made of soft wood, such as willow, 19 is the sole part of the foot, ordinarily made of felt, and 20 is the tongue of hard wood which, as the drawings show, is dovetailed in the part 115 18 above and the part 19 below. In this foot construction the socket in the foot member for the springs 13 and 14^a will preferably be carried down to the hard wood tongue 20. Another bolt, 22, extending 120 through the component parts of the foot at the anterior end, binds the whole more securely together. The form of the bolt which I have found best adapted in this construction consists of a sleeve provided with an 125 angular countersunk head 23, which extends through a hole in the foot made to receive it. The sleeve is threaded within at its lower end; and, engaging this thread portion, is a screw 24, whose head is counter- 129

sunk in the opposite surface of the foot, and the parts of the bolt are drawn together to firmly unite the parts. This bolt 22 extends through the tongue 20 as well as through the body of the upper part of the foot and sole adds to the strength of the structure as a whole. The bolt 22 may conveniently be employed to engage one end of the elastic band 21 (the opposite forward end thereof being secured to the sole body) and hold the band secure in tense position.

I claim herein as my invention:

1. In a joint for an artificial limb, the combination of two limb members provided with corresponding hinge-knuckles, and a hinge-pin removably engaging said knuckles and completing the joint, and when in position extending adjacent to the surface of one of said limb members, and means for securing said hinge-pin against said surface, substantially as described.
2. In a joint for an artificial limb the combination of a limb member, a bolt whose shank extends through the body of said limb member and whose head protrudes from one surface thereof, such protruding head being shaped to form a hinge-knuckle, a hinge-pin removable in said hinge-knuckle, and when in place therein extending adjacent to the aforesaid surface of the limb member, and a nut upon the shank of said bolt securing said bolt in the limb member and holding said hinge-pin against the aforesaid surface, substantially as described.
3. In a joint for an artificial limb, the combination of two limb members, articulated together by a joint, the members of said joint being provided with abutting surfaces which limit the hinge movement in one direction, the said limb members being provided with surfaces which yieldingly engage one another as the abutting surfaces of the joint approach one another.
4. In an ankle joint for an artificial leg the combination of a solid leg member and a foot member articulated together by a joint which limits the forward swing of the foot member upon the leg member, the said foot and leg members being provided with surfaces on the anterior side of said joint which yieldingly engage one another as the forwardly swinging foot approaches the limit of its jointed movement, the said leg member being reinforced by a block of relatively hard and tenacious material at the

point where the said yielding engagement is made with the foot member, such reinforcing block being sunk in the solid body of said leg member, substantially as described.

5. An artificial foot comprising a sole body, an upper body and a strip extending longitudinally between, to which said sole and upper bodies are dovetailed, substantially as described.

6. An artificial foot comprising a sole body of felt, an upper body of soft wood and an interposed tongue of hard wood upon which said sole and upper bodies are dovetailed, substantially as described.

7. An artificial foot comprising a sole body, an upper body and an interposed uniting strip of relatively hard and tenacious material, said foot being adapted to be hinged to an artificial leg body, said foot being provided with a socket for a spring, sunk through the upper body thereof to the said uniting strip, substantially as described.

8. An artificial foot comprising a sole body, an upper body, and an interposed uniting tongue of relatively hard and tenacious material, an elastic strip extending upon the ball of the foot, said strip being rigidly secured at one end to said sole body, and a bolt, extending through said foot and through the said tongue of hard material therein, engaging the otherwise free end of said elastic strip, and while securing the component parts of said foot serving also to hold tense said elastic strip, substantially as described.

9. An artificial foot comprising a plurality of built up parts and a bolt extending through and uniting said parts, said bolt consisting of a sleeve extending through a hole in the foot formed to receive it, an angular head upon said sleeve engaging a correspondingly shaped recess in the surface of said foot, a screw thread formed upon the inner surface of said sleeve, and a screw entering the hole through said foot opposite to the head formed upon the said sleeve and engaging the internal thread of said sleeve, substantially as described.

In testimony whereof, I have hereunto set my hand.

ENGELBERT MUELLER.
